RUG AND CARPET CLEANING DEVICE
Nishan E. Buruchian, 427 Marlboro Road,
Wood Ridge, N.J.
Filed Feb. 9, 1965, Ser. No. 431,317
18 Claims. (Cl. 68—20)

The invention relates to rug and carpet cleaning devices and in particular to a rug and carpet cleaning device which does not stretch or shrink the rug or carpet during the cleaning process.

Up to the present time it has not been possible to remove wall-to-wall carpets for cleaning because the carpet changed its shape and size during the cleaning process and could not be relaid properly. As a result, most carpets are cleaned in the home with considerable inconvenience and inadequate cleaning. In order to clean a rug or carpet satisfactorily, it is necessary to clean both the pile and backing thoroughly. This is not possible if the carpet must be cleaned while it remains tacked to the floor. Proper cleaning requires that the cleaning solution (soap and water or a chemical cleaner) flows through the pile and the backing so that the dirt is removed from all the openings and crevices in the carpet or rug. For good results, it is also necessary for the rug or carpet to be thoroughly rinsed and spin or air dried. This is not possible if the carpet or rug remains on the floor and the pile is shampooed.

It is an important object of the invention to provide a rug and carpet cleaning device in which a rug and carpet can be thoroughly cleaned and which prevents the rug or carpet from stretching or shrinking during the cleaning process.

It is a further object of the invention to provide such a cleaning device wherein the rug or carpet is held in a spiral within the device and is rotated so that the cleaning solution acts on both surfaces of the rug or carpet and flows through the pores and crevices of the rug or carpet.

It is still a further object of the invention to provide such a cleaning device into which hot air may be introduced while the spiral is rotated so as to dry the rug or carpet.

It is a still further object of the invention to provide such a cleaning device wherein more than one rug or carpet may be cleaned at the same time.

These and other objects, advantages, features and uses will be apparent during the course of the following description when taken in conjunction with the accompanying drawings wherein:

FIGURE 1 is a diagrammatic, end elevational view, partly in section, of a preferred embodiment of the rug and carpet cleaning device of the invention;

FIGURE 2 is a diagrammatic, sectional view, partly in elevation, of the rug and carpet cleaning device of FIGURE 1, taken on line 2—2 of FIGURE 1, viewed in the direction of the arrows;

FIGURE 3 is an elevational view of one form of end element used in the cleaning device of the invention, viewed in the direction of the arrows 3—3 of FIGURE 4A.

FIGURES 4 and 4A are sectional views of the preferred forms of end elements used in the cleaning device of the invention which is equipped for steam drying;

FIGURE 5 is an enlarged view, partly in section, showing the conveyor which is a part of the cleaning device of FIGURE 1, rolled up;

FIGURE 6 is an elevational view showing a rug affixed to the conveyor of the invention and showing the means for joining the sections of the conveyor;

FIGURE 7 is an illustration of a typical hook used to hold the end of a rug in position within the cleaning device of the invention;

FIGURE 8 is a top plan view of the washing and drying section of the cleaning device of the invention, with the lid closed;

FIGURE 9 is a plan view of the roller assembly used to feed the rug or carpet onto the conveyor for insertion into the washing and drying section of the cleaning device of the invention;

FIGURE 10 is an enlarged section of a portion of the spiral guide used in the cleaning device of the invention, showing the openings for distributing steam for drying the rugs or carpets; and

FIGURE 11 is an enlarged plan view of a portion of the conveyor, showing its connection to the cable provided for pulling the conveyor into the washing and drying section of the cleaning device of the invention.

In the drawings, wherein, for the purpose of illustration, is shown a preferred embodiment of the invention, the numeral 20 designates the tank which encloses the washing and drying section of the rug and carpet cleaning device of the invention. Tank 20 is provided with a lid 22 which is closed during the cleaning operation. Spiral guide 24, which is mounted in tank 20 on axle 26, is preferably liquid impervious and is used to guide the conveyor into position. It may also be formed of a rigid mesh material on which the conveyor is guided and rests. Spiral guide 24 may be a unitary element extending almost the full width of the tank or it may be two or more spaced guides which support the conveyor at its sides and, if desired, at intermediate areas.

Conveyor 28 is mounted in a roll on axle 30 when it is not drawn into tank 20 and the rug or carpet 32 to be cleaned is mounted as shown in FIGURE 1. Conveyor 28 is pulled onto spiral guide 24 into tank 20 by means of pulley 34 and cable 36. After the conveyor 28 and rug 32 are completely inside tank 20, the conveyor end is affixed to the spiral guide by means of hooks 62 or similar devices and lid 22 is closed and the combination is rotated on axle 26 by means of motor 38 in a clockwise direction as viewed in FIGURE 1. Cleaning solution is introduced into tank 20 through pipe 40 and moves to the bottom of the tank 20 due to the force of gravity. The ends of the combination of spiral guide, conveyor and rug are enclosed by a pair of end plates 42 and 43 at least one of which has central opening 23 such as is illustrated in FIGURE 3. When spaced spiral guides are used, the outer end of at least one of them is provided with an end plate having a central opening. Preferably, the other end plate affixed to the outer end of the other spaced spiral guide is closed to preclude ejection of the fluid from that end.

The tank is filled with cleaning solution to an appropriate level and the combination is rotated. As the combination is rotated, cleaning solution is drawn up within the spiral until it fills the spiral and is ejected through the central opening 23 in end element 42. As the rotation is continued, the cleaning solution is circulated through the spiral and the rug or carpet is cleaned. After the rug is cleaned, a drain cock (not shown) at the end of pipe 46 is opened and the spiral continues to rotate. All the solution is thereby ejected from the spiral and is drained from the tank. The solution, so drained, may be discarded or pumped back into the supply tank, as desired.

Next, rotation is stopped, the drain cock at the end of pipe 46 is closed and a rinsing solution is introduced into the tank through pipe 40. The tank is filled with rinsing solution to the required level and the spiral guide, conveyor and rug are rotated so that the rinsing solution is run over the complete rug and is ejected from opening 23. Rinsing continues for the required time and then the drain cock is opened and the rinsing solution is ejected from the tank. If desired, more than one rinsing cycle may be

used or under certain conditions, rinsing may be dispensed with.

To facilitate drying of the rug 32, the spiral is rotated while hot air is blown into tank 20 through line 48 and leaves tank 20 through line 50. It is also within the contemplation of the invention to provide heating elements within the conveyor or the spiral guide. These, in the preferred embodiment, may take the form of electrical heater elements embedded in the conveyor or spiral guide in a manner well-known in the art. Details of the heating elements and the means for applying voltage thereto are not shown.

It is also within the contemplation of the invention to utilize steam for drying the rug and/or carpet which has been cleaned. Such a cleaning device would be provided with end elements 42 and 43 which are illustrated in FIGURES 3, 4 and 4A. Openings 51 in the end elements 42 and 43 match openings 25 in spiral guide 24 so that steam can be fed into the system through opening 45 in axle 26, out through openings 47 in axle 26 into the chamber in end element 43 (FIGURE 4). The steam then flows through openings 51 in end element 43 into channels 25 in spiral guide 24. The steam then flows through channels 25 and exits through openings 51 into the chamber in end element 42 (FIGURE 4A). The steam leaves the chamber in end element 42 through release valve 49. End element 42 is mounted to axle 26 by means of struts 44. The flow of water being ejected from the spiral during washing is not blocked by these struts.

Detailed views of conveyor 28 are shown in FIGURES 5, 6 and 11. In FIGURE 5, conveyor 28 is seen to comprise base 52 on which are mounted spikes 54 to hold the rug. Openings 56 are provided in base 52 to permit the solution to flow through the rug. Ribs 58 are used to hold the conveyor so that the spikes from one layer do not pierce the next layer when the conveyor is rolled up on axle 30 (FIGURE 1). In FIGURE 11 there are shown a pair of joined slats of conveyor 28 connected by means of hinges 60 which permit the conveyor, which is preferably formed of rigid slats of aluminum or plastic, to follow the contour of the spiral guide. There may be more than one pulley 34 and cable 36 spaced along axle 26 used to pull the conveyor and rug onto the spiral guide evenly. FIGURE 6 shows the relationship of the elements of the conveyor and the rug before the combination starts to follow the curve of the spiral.

In FIGURE 7 there is shown hook 62 which is provided with barbs 64 which are hooked, if desired, into the conveyor and the rug to hold the leading and trailing ends of the rug in place on the conveyor and to hold the conveyor in place on the spiral guide.

FIGURE 9 illustrates the rollers on which the rug 32 is placed prior to and after cleaning and the motors for re-rolling the rug and the conveyor. Roller 68 serves to force rug 32 onto spikes 54 as the conveyor is pulled into the tank. After the rug is cleaned, the rug is moved back into a roll above rollers 66 and 70. Conveyor 28 is moved out of the tank and into a roll by means of motor 73. When this action takes place, rollers 66 and 70 are driven by motor 72 to roll the rug. Preferably, roller 68 should be raised out of contact with the rug during this operation.

If the size of the rugs or carpets being cleaned permits, more than one rug or carpet may be cleaned at the same time.

Operation of the rug and carpet cleaning device of the invention proceeds as follows: cable 36 is hooked onto the end of conveyor 28 and pulley 34 is caused to rotate to pull the conveyor into tank 20. Pulley 34 may be actuated by motor 38 through a standard clutch (not shown) which permits pulley 34 to rotate while axle 26 and spiral guide 24 remain stationary. The leading end of rug 32 is hooked onto conveyor 28. As the conveyor is pulled into the tank, the weight of roller 68 forces rug

32 onto pins 54. The leading end of rug 32 may be held to conveyor 28 by using one or more hooks 62. The hooks are also used to hold the trailing end of the rug to the conveyor.

After the conveyor 28 and the rugs or carpets to be cleaned have been pulled into the tank, pulley 34 is stopped. Lid 22 is closed, the clutch is operated to allow axle 26 and spiral guide 24 to rotate and cleaning solution enters the tank through pipe 40. When sufficient cleaning solution has entered the tank, the feed through pipe 40 is cut off. Now motor 38 is turned on and the combination is rotated clockwise. This causes the cleaning solution to feed through the spiral and to be ejected back into the tank through opening 23 in end element 42. This operation continues for the required washing time.

Next, a valve (not shown) affixed to pipe 46 is opened and while spiral guide 24, conveyor 28 and the rugs continue to spin, the cleaning solution is ejected from the combination and drained from the tank.

If air drying is to be used, hot air is blown into pipe 48 from a source (not shown) while the spiral continues to spin. The air leaves through pipe 50.

If steam drying is to be used, the spiral is spun and steam from a source (not shown) is forced into opening 45 in axle 26 and through openings 47 into the chamber in end element 43. From the chamber it enters channels 25 through openings 51 so that the interior of spiral guide 24 is permeated with steam. The steam exits from the spiral through openings 51 into the chamber in end element 42 from which it leaves through valve 49.

When the rug or rugs are completely dry, the spiral is stopped from spinning and a cable similar to cable 36 is connected between conveyor 28 and axle 30. Hooks 62 are removed and conveyor 28 is pulled onto axle 30 by means of motor 73. At the same time, the end of rug 32 is placed on rollers 66 and 70 and they are rotated by motor 72. This causes the rug to roll up. When the rug is completely rolled up and the conveyor is rolled up on axle 30, the motors are turned off and the device is ready for further cleaning.

While a particular embodiment of the invention has been shown and described, it is apparent to those skilled in the art that modifications, including substituting a dyeing step for the washing step, are possible without departing from the spirit of the invention or the scope of the subjoined claims.

What is claimed is:

1. A rug and carpet cleaning device comprising:
a tank;
a rotatable spiral guide mounted within the tank;
a conveyor having means, as a part thereof, for holding the article to be cleaned in position;
means for moving the conveyor onto the rotatable spiral guide;
means for introducing cleaning solution into the tank; an end plate affixed to each end of the rotatable spiral guide;
one of the end plates having a central opening therein;
means for rotating the spiral guide, the conveyor and the article held thereto so that the cleaning solution is drawn up inside the combination and is ejected through the central opening in the end plate having the central opening; and
means for draining the cleaning solution from the tank.
2. A rug and carpet cleaning device as described in claim 1 including means for storing the conveyor, means for mounting the article to be cleaned prior to affixing it to the conveyor and means for feeding the article to be cleaned onto the conveyor.
3. A rug and carpet cleaning device as described in claim 2 wherein the end plates have openings therein and the spiral guide has a plurality of openings running the width thereof, the openings in the end plates com-

municating with the openings in the spiral guide to permit steam to be fed within the spiral guide.

4. A rug and carpet cleaning device as described in claim 1 wherein the conveyor comprises a plurality of strips hinged together to permit the conveyor to follow a curved path and the means for holding the article to be cleaned in position comprises a plurality of spikes projecting upward from the conveyor. 5

5. A rug and carpet cleaning device as described in claim 4 including means for storing the conveyor, means for mounting the article to be cleaned prior to affixing it to the conveyor and means for feeding the article to be cleaned onto the conveyor. 10

6. A rug and carpet cleaning device as described in claim 5 wherein the end plates have openings therein and the spiral guide has a plurality of openings running the width thereof, the openings in the end plates communicating with the openings in the spiral guide to permit steam to be fed within the spiral guide. 15

7. A rug and carpet cleaning device as described in claim 4 wherein the end plates have openings therein and the spiral guide has a plurality of openings running the width thereof, the openings in the end plates communicating with the openings in the spiral guide to permit steam to be fed within the spiral guide. 20

8. A rug and carpet cleaning device as described in claim 1 wherein the end plates have openings therein and the spiral guide has a plurality of openings running the width thereof, the openings in the end plates communicating with the openings in the spiral guide to permit steam to be fed within the spiral guide. 30

9. A rug and carpet cleaning device comprising:

a tank;
a pair of spaced, rotatable spiral guides mounted within the tank;
a conveyor having means, as a part thereof, for holding the article to be cleaned in position;
means for moving the conveyor onto the pair of spaced, rotatable spiral guides;
means for introducing cleaning solution into the tank; 40
a closed end plate affixed to the outer end of one of the pair of spaced, rotatable spiral guides so as to preclude the ejection of cleaning solution;
an end plate having a central opening therein affixed to the outer end of the other of the pair of spaced, rotatable spiral guides; 45
means for rotating the pair of spaced, rotatable spiral guides, the conveyor and the article held thereto so that the cleaning solution is drawn up inside the combination and is ejected through the central opening in the end plate having the central opening; and
means for draining the solution from the tank. 50

10. A rug and carpet cleaning device as described in claim 9 wherein the conveyor comprises a plurality of strips hinged together to permit the conveyor to follow a curved path and the means for holding the article to be cleaned in position comprises a plurality of spikes projecting upward from the conveyor. 55

11. A rug and carpet cleaning device as described in claim 10 including means for storing the conveyor, means for mounting the article to be cleaned prior to affixing it to the conveyor and means for feeding the article to be cleaned onto the conveyor. 60

12. A rug and carpet cleaning device as described in claim 9 including means for storing the conveyor, means for mounting the article to be cleaned prior to affixing it to the conveyor and means for feeding the article to be cleaned onto the conveyor. 65

13. A rug and carpet cleaning device comprising:
a tank;

a pair of spaced, rotatable spiral guides mounted within the tank;

a conveyor comprising a plurality of strips hinged together to permit the conveyor to follow a curved path and a plurality of spikes mounted on the strips for holding the article to be cleaned on the conveyor;

means for storing the conveyor outside the tank;
means for mounting the article to be cleaned prior to affixing it to the conveyor;

means for moving the conveyor onto the pair of rotatable, spiral guides while affixing the article to be cleaned to the conveyor;

at least one end plate having a central opening therein affixed to one of the pair of rotatable, spiral guides; means for introducing cleaning solution into the tank; means for rotating the pair of rotatable, spiral guides, the conveyor and the article held thereto so that the cleaning solution is drawn up inside the combination and is ejected through the central opening in the end plate having the central opening; and means for draining the cleaning solution from the tank.

14. A rug and carpet cleaning device as described in claim 13 including a closed end plate affixed to one of the pair of rotatable, spiral guides. 25

15. A rug and carpet cleaning device comprising:

a tank;
a rotatable spiral guide mounted within the tank;
a conveyor comprising a plurality of strips hinged together to permit the conveyor to follow a curved path and a plurality of spikes mounted on the strips for holding the article to be cleaned on the conveyor; means for storing the conveyor outside the tank;
means for mounting the article to be cleaned prior to affixing it to the conveyor;
means for moving the conveyor onto the rotatable spiral guide while affixing the article to be cleaned to the conveyor;

at least one end plate, having a central opening therein affixed to the rotatable, spiral guide;

means for introducing cleaning solution into the tank;

means for rotating the rotatable, spiral guide, the conveyor and the article held thereto so that the cleaning solution is drawn up inside the combination and is ejected through the central opening in the end plate having the central opening; and

means for draining the cleaning solution from the tank.

16. A rug and carpet cleaning device as described in claim 15 including a closed end plate affixed to one end of the rotatable, spiral guide. 50

17. A rug and carpet cleaning device as described in claim 16 wherein the end plates have openings therein and the spiral guide has a plurality of openings running the width thereof, the openings in the end plates communicating with the openings in the spiral guide to permit steam to be fed within the spiral guide. 55

18. A rug and carpet cleaning device as described in claim 15 wherein the end plates have openings therein and the spiral guide has a plurality of openings running the width thereof, the openings in the end plates communicating with the openings in the spiral guide to permit steam to be fed within the spiral guide. 60
